UNITED STATES PATENT OFFICE.

ERIC H. GOLDEN, OF LEWISTOWN, MISSOURI.

TREATING-CABINET.

1,364,365.

Specification of Letters Patent.

Patented Jan. 4, 1921.

Application filed April 19, 1920. Serial No. 375,037.

To all whom it may concern:

Be it known that I, ERIC H. GOLDEN, a citizen of the United States, residing at Lewistown, Missouri, have invented certain new and useful Improvements in Treating-Cabinets, of which the following is a full, clear, and exact description, such as will enable others skilled in the art to which it appertains to make and use the same.

10 This invention relates to treating cabinets of the kind that are used by physicians and specialists for administering a vapor bath or hot air bath to a patient.

One object of my invention is to provide 15 a means by which a vapor, a medicant or heat can be applied to the body or portions of the body of a person in such a manner that the nervous system of the person will not undergo a shock produced by subjecting 20 the person's body to sudden extreme variations in temperature.

Another object is to provide a means by 25 which a treating medium can be applied to a person in such a manner that the pores of the person's skin will gradually open, thus permitting the treating medium to enter the pores, and thereafter will close before the completion of the treating operation.

Another object is to provide a vapor bath 30 cabinet that can be accurately regulated to cause a vapor or a current of air, either hot or cold air, to circulate over the body of the occupant of the cabinet, or over portions of the occupant's body, such, for example, 35 as the legs or the arms.

And still another object is to provide a vapor bath cabinet that can be used successfully for treating the body and the head of the patient with a treating medium.

40 To this end I have devised a treating cabinet which consists of a closed housing constructed to receive a person and provided with means whereby different sections of same that receive different portions of the 45 patient's body can be divided off into separate compartments, means for gradually heating and thereafter cooling the occupant's body, or portions of the body, and means for administering a treating medium

50 to the occupant, preferably a treating medium consisting of a mixture of one or more medicated vapors or fumes, or simply a current of hot, dry air. The treating medium and also the air used to cool the per-

55 son is forced over the patient's body and circulated through the cabinet by a fan, and

means is provided for establishing and cutting off communication between the body compartment and the head compartment, thus enabling the body or the body and head 60 of the patient to be treated. In the form of my invention herein illustrated means is also employed for enabling a section of the body compartment to be cut off or separated from the remainder so as to form a chamber 65 in which the extremities of a person can be treated. I prefer to construct the cabinet so that three separate circulations through the cabinet can be obtained: First, what I will term the body circulation consisting of 70 a current of dry hot air, or a mixture of heated vapors or fumes of a gradually increasing temperature that pass from a mixing chamber over the body of the patient, and then return to the mixing chamber; sec 75 ond, what I will term the body and head circulation consisting of thoroughly mixed and heated vapors or fumes of a gradually increasing temperature that pass from the mixing chamber over the body and the head 80 of the patient and then preferably escape from the cabinet; and third, what I will term the body cooling circulation consisting of a current of cool air of gradually decreasing temperature that is drawn from a cooling chamber and forced over the patient's body by a fan. Valves operated from the exterior of the cabinet are provided for governing the circulation of the treating 85 medium or the cooling air through the cabinet, and a device, preferably a slatted partition or group of spaced shutters, is arranged between the fan and the body compartment of the cabinet so as to break up the current produced by the fan, and thus 90 cause the treating medium or the air to be distributed uniformly over the body of the patient, or over portions of the patient's body. The fan is preferably driven at a comparatively slow speed by an electric motor, and if desired, means can be used for actuating a signal automatically after the patient has been in the cabinet a certain length of time, so as to notify the attendant 95 in charge of the patient.

100 Figure 1 of the drawings is a perspective view of a vapor bath cabinet constructed in accordance with my invention.

Fig. 2 is a horizontal sectional view, taken on the line 2—2 of Fig. 3.

110 Fig. 3 is a vertical longitudinal sectional view of the cabinet; and

Figs. 4, 5 and 6 are vertical transverse sectional views of the cabinet, taken on approximately the lines 4-4, 5-5 and 6-6, respectively, of Fig. 3, looking in the direction indicated by the arrows.

Referring to the drawings which illustrate the preferred form of my invention, A designates a casing or housing of any preferred construction and design whose interior is divided by suitable partitions so as to form a body compartment B, a head compartment C, a mixing chamber D, a cooling chamber E, a fan chamber F and a discharge chamber G. The left-hand end portion of the body compartment B, looking at Fig. 3, is preferably divided or cut off from the remainder by a vertically-disposed partition so as to form a chamber B' in which the arms or the legs of a person can be treated independently of other portions of the patient's body. An inclined support 1 for the occupant of the cabinet is arranged in the compartments B and B' and a support 2 for the occupant's head is arranged in the head compartment C, said body and head supports being of any preferred shape and construction, but preferably provided with perforations, slots or openings through which the treating medium or the air can circulate. The fan chamber F is connected with the mixing chamber D and with the cooling chamber E by openings 3 and 4, respectively, formed in the partitions between said chambers, and a valve 5 is provided for establishing and cutting off communication between said chambers. The valve 5 of the cabinet herein shown is a hinged valve which is so arranged that when it is in its vertical position, as shown in Fig. 3, communication is established between the mixing chamber D and the fan chamber F, the cooling chamber E being then cut off from the fan chamber. When said valve 5 is in its horizontal position, communication will be established between the cooling chamber E and the fan chamber F, the mixing chamber D then being cut off from the fan chamber, due to the fact that the valve 5 closes the opening 3. I have herein shown the valve 5 provided with a controlling device 6 that projects outwardly through the end wall of the fan chamber, but I wish it to be understood that it is immaterial, so far as my invention is concerned, what particular type or kind of valves and valve controlling devices the cabinet is provided with, so long as they are of such construction that the valves can be operated or adjusted easily from the exterior of the cabinet, thus enabling the flow of the treating medium or the air through the cabinet to be easily regulated.

A fan 7 is arranged in the fan chamber F and a slatted partition or shutter device 8 is arranged between the fan chamber and the adjacent end section of the body com-

partment B, so as to break up the current produced by the fan, and thus cause the treating medium or the air that circulates through the cabinet to be distributed uniformly over the body of the patient being treated. I have herein shown the fan 7 operated by an electric motor 9 with a timing mechanism combined with the fan in such a manner that a signal will operate automatically after the patient has been in the cabinet a certain length of time, and thus notify the attendant in charge of the patient that the treatment has been completed and that the patient should be removed from the cabinet. Any suitable type of timing mechanism may be used and any suitable means can be employed for driving the fan 7 from the motor 9, so long as it is of such design that the fan will revolve slowly. In the cabinet herein shown a belt 10 is used for driving the fan 7, said belt traveling over a small pulley on the armature shaft of the motor and over a large pulley on the shaft 11 of the fan. The timing mechanism that is used for operating the signal automatically may consist of a gear 12 operated intermittently by means of a pin 13 on the fan shaft and arranged so that it will move a contact 14 to close an electric circuit in which a signal is arranged. In Fig. 2 the gear 12 of the timing mechanism is shown as having only a few teeth, but in practice a gear provided with a relatively great number of teeth would be employed so as to require considerable time for the gear to make a complete revolution.

The mixing chamber D is provided with a heating means, preferably a number of gas burners 15, as shown in Fig. 3, and receptacles 16 that are arranged in proximity to said gas burners are adapted to hold a treating substance, usually a substance which will throw off fumes or produce a vapor when subjected to heat. Openings 17 are formed in one wall of the mixing chamber D, as shown in Fig. 3, so as to admit air to said chamber, and if desired, said chamber can be provided with a door 18 so as to supply additional air and also to give access to the mixing chamber, either for the purpose of replenishing the material in the receptacles 16 or to regulate the burners 15.

The body compartment B is connected with the mixing chamber D by means of a passageway 19 that has an inclined portion, as shown in Fig. 3, so that the products of condensation which collect in said passageway will drain back into a drain receptacle 20 in the mixing chamber D. A valve 21 is mounted in the passageway 19 in such a manner that it can be moved into the position shown in broken lines in Fig. 3, so as to establish communication between the body compartment B and the cooling chamber E through an opening 21^a in one wall of said

passageway, or into the position shown in full lines in Fig. 3, so as to close the opening 21^a and thus establish communication between said body compartment and the 5 mixing chamber D. When the valve 21 is in the position shown in full lines in Fig. 3 the vapor that is drawn from the mixing chamber by the fan 7 and forced into the body compartments B will return to said 10 mixing chamber through the passageway 19. The valve 21 is equipped with a controlling device 22 that leads to the exterior of the cabinet so as to enable said valve to be opened and closed by the attendant in 15 charge of the cabinet. A valve 23, preferably a slide valve, is also provided for preventing circulation from the body compartment into the passageway 19 or into the cooling chamber E when the head of the 20 patient is being treated, said valve 23 being equipped with a controlling device 24 that leads to the exterior of the cabinet. In practice the controlling devices 22 and 24 for the valves 19 and 23, respectively, lead 25 outwardly through the rear wall of the cabinet, but for convenience in illustrating the invention I have shown the controlling device 24 as leading outwardly through the end wall of the cabinet. The passageway 30 19 is provided with a branch 19^a that leads upwardly to the end section B' of the body compartment and a valve 23^a is provided for normally closing the lower end of said branch. The upper end of said branch is 35 normally closed by a cap 23^b. When it is desired to use the cabinet for treating the legs of a person the valve 23^a is opened and the cover 23^b is removed so as to cause the treating medium to circulate from the mixing 40 chamber D through the chamber B' and then back to said mixing chamber through the branch 19^a of the passageway 19, it being the usual practice to protect the patient's feet with a hood 1^a arranged in the chamber 45 B'. If a person's arm is to be treated the arm is introduced into the chamber B' through an opening in the front wall of the cabinet that is normally closed by a slide door 33^a, as shown in Fig. 1.

50 A slide partition 25 is arranged between the body compartment B and the head compartment C, which partition is provided in its lower edge with a notched portion 25^a, as shown in Fig. 4, that conforms to the 55 shape of the neck of the occupant of the cabinet. When said partition 25 is in its depressed position communication will be cut off between the body compartment and the head compartment, and when said slide 60 door is in its elevated position, the treating medium that is supplied to the body compartment will also circulate through the head compartment. If desired, a thermometer 26 can be arranged in the head compartment in such a position that it can be ob-

served by the occupant, said head compartment can be equipped with an electric light bulb 27, and a switch 28 can also be provided so as to enable the occupant to signal the attendant in charge of the cabinet. 70

The casing or outer shell of the cabinet can be formed from any suitable material, and can be of any preferred design. The walls of the head compartment C are preferably made of glass and comprise an inclined top wall 29, an end wall 30 and side panels 31 hinged together so as to form a single unit that can be applied and removed easily. The front wall of the cabinet is provided with a door 33 through which the patient can enter the body compartment B, or if desired, the entire upper portion of the cabinet can be raised to admit the patient, said upper portion which is designated by the reference 75 character 34 being hinged at 35 to the rear wall of the cabinet, as shown in broken lines in Fig. 1. Doors 36 and 37 are formed in the rear wall and in the right hand end wall of the cooling chamber E, and a door 38 is formed in the end wall of the discharge chamber G. The fan chamber F is also preferably provided with a door 39 through which access can be had to said chamber, and a door 39^a is arranged in the 90 front wall of the cabinet, so as to give access to the burners 15.

An inclined drain 40 that is arranged under the support 1 on which the body of the patient rests is provided with a drain pipe 41 whose lower end is arranged in alinement with a waste pipe 42, the upper end of said drain pipe 41 being normally closed by a cap 43 carried by a lever 44 which is so arranged that it will coöperate with a device 100 45 on the front door 33 of the body compartment to raise said cap automatically when said door is closed and to lower said cap so as to close the drain pipe 41 when said door 33 is opened. At the lower end of the drain pipe 41 is a flanged collar 46 that extends over a waste pipe 47, said collar being normally held in engagement with said waste pipe by means of a latch 48.

If it is desired to subject the body of the 115 patient to a vapor bath the patient is first placed in the cabinet and the valves are so arranged that a circulation will be created from the mixing chamber D through the body compartment B and then back to the 120 mixing chamber through the passageway 19, as indicated by the solid arrows in Fig. 3, this being accomplished by arranging the valve 4 in its vertical position, the valve 21 in its vertical position, the valve 23 in its retracted position, namely, out of alinement with the upper end of the return passageway 19, and the slide partition 25 between the body compartment B and the head compartment C in its depressed position. The 125 130

burners 15 under the receptacles 16 are then lighted so as to vaporize the substance in said receptacles and the fan 7 is then started, so as to cause a heated current of air and medicated vapor of gradually increasing temperature to be distributed uniformly over the body of the patient. The fan 7 revolves at a comparatively slow speed, and as the heat is applied to the body of the patient gradually, the nervous system of the patient will not undergo a shock, as would be apt to occur if the patient's body were subjected to a sudden blast of highly heated vapor. In my improved cabinet all portions of the patient's body are subjected to the same degree of heat, the temperature of which is gradually increased as the treating operation proceeds, thus causing the pores of the patient's body to open gradually as the treating operation proceeds. If the body of the patient is to be subjected merely to a hot air bath, the receptacles 16 are removed and one or more of the burners 15 are used to heat air which is circulated over the body of the patient by the fan 7. If it is desired to treat the head of the patient, as well as the body, the slide partition 25 is moved upwardly, the valve 23 is moved into a position to cut off communication between the body compartment B and the return passageway 19 and the door 38 in the discharge chamber G is opened. Thereafter, the heated vapors or fumes that are drawn from the mixing chamber D by the fan 7 will be forced into the body compartment B and will circulate from said body compartment through the head compartment, and thence into the discharge chamber G, as indicated by the dotted arrows in Fig. 3, finally escaping from said discharge chamber to the atmosphere through the opening in same that is normally closed by the door 38.

After the patient has been treated with medicated vapors or with hot air in the manner above described, the patient's body is gradually cooled so as to permit the pores of the skin to close before the patient leaves the cabinet. This gradual cooling of the patient is effected by moving the valve 4 into its horizontal position so as to cut the mixing chamber D out of service and establish communication between the cooling chamber E and the fan chamber, the valve 21 being moved into its horizontal position shown in broken lines in Fig. 3, so as to close the return passageway 19 and establish communication between the body compartment B and the cooling chamber E, the door 37 in the end wall of the cooling chamber E being opened so as to admit fresh air to said chamber. Thereafter, a current of air of gradually reducing temperature will be distributed uniformly over the body of the patient.

A cabinet of the construction above de-

scribed makes it possible to treat the body of a patient with a medicated vapor or with hot air in such a manner that the nervous system of the patient is not subjected to a shock, due to the fact that the patient's body is heated gradually and is thereafter cooled gradually, the gradual heating of the body causing the pores to open in such a way that the treating medium can penetrate into same efficiently and thereafter close or return to their normal condition before the patient leaves the cabinet. Furthermore, such a cabinet makes it possible to treat the head as well as the body of the patient, or treat the arms or the legs independently of other portions of the body. If desired, the head compartment can be ventilated by raising the hinged members 29, 30 and 31 of the head compartment, in case the treating medium is of such a character that it is not desired to have it come in contact with the head of the patient.

Having thus described my invention, what I claim as new and desire to secure by Letters Patent is:

1. A treating cabinet provided with a compartment for receiving the body of the occupant and a compartment for receiving the head of the occupant, and means for forcing a treating medium through the body compartment or through the body and head compartments.

2. A treating cabinet, comprising a casing provided with a compartment for receiving the occupant, a chamber in said casing provided with means for heating a treating medium, means for drawing said heated treating medium from said chamber, forcing said medium through said compartment over the entire body of the occupant and then returning said medium to said chamber, and means for controlling the circulation of said medium.

3. A treating cabinet provided with a compartment for receiving the occupant, a chamber provided with means for heating a treating medium, a separate chamber to which air is supplied, and means whereby circulation can be established either between said compartment and the chamber in which the treating medium is heated or between said compartment and the chamber to which air is supplied.

4. A treating cabinet provided with a compartment for receiving the occupant, a chamber provided with means for heating a treating medium, and means whereby said heated treating medium can be drawn from said chamber and circulated through said entire compartment or through a section of said compartment and then returned to said chamber.

5. A treating cabinet provided with a compartment for receiving the occupant, a mixing chamber provided with means for

heating a treating medium, an air chamber, a fan chamber provided with a fan for creating a circulation in said compartment, and means whereby the air in said air chamber or the heated treating medium in said mixing chamber can be supplied to said fan chamber.

6. A treating cabinet provided with a compartment for receiving the occupant, a fan chamber separated from said compartment by a slatted partition or similar means, a fan in said fan chamber, and means for enabling a heated treating medium or a cooling medium to be supplied to said fan chamber.

7. A treating cabinet provided with a body compartment and a head compartment, an adjustable means that is adapted to be arranged in one position so as to establish communication between said compartments and in a different position so as to cut off communication between said compartments, means for forcing a treating medium through both of said compartments or 25 through only the body compartment, and means whereby the force and volume of said medium may be varied.

8. A treating cabinet provided with a compartment for receiving the occupant, a mixing chamber provided with a means for heating a treating medium, means for drawing the treating medium from said mixing chamber and forcing said medium through said compartment over the body of 30 the occupant, means for controlling the volume of the treating medium supplied to said chamber, and a passageway leading from said compartment back to said mixing chamber.

40 9. A treating cabinet provided with a compartment for receiving the occupant, a mixing chamber provided with a means for heating a treating medium, means for drawing the treating medium from said mixing chamber and introducing it into said compartment, a passageway leading from said compartment back to said mixing chamber, an air chamber, and means for enabling said mixing chamber to be cut out of service, and 45 a circulating passageway established between said air chamber and said compartment.

50 10. A treating cabinet provided with a compartment for receiving the occupant, a mixing chamber, means that divides said compartment into a number of sections, passageways leading from the sections of said compartment to said mixing chamber, and a fan for creating a circulation through said compartment, passageways and mixing chamber.

55 11. A treating cabinet provided with a compartment for receiving the occupant, a fan chamber separated from said compartment by a slatted partition or similar means,

a mixing chamber, an air chamber, means for establishing communication either between said fan chamber and said mixing chamber or between said fan chamber and air chamber, means for admitting air to said air chamber, a passageway leading from said compartment to said mixing chamber, and a controlling valve in said passageway.

60 12. A treating cabinet provided with a compartment for receiving the occupant, a drain pipe leading from said compartment, a closure for the upper end of said drain pipe, a door for said compartment, and means for moving said closure into and out of operative position when the door of said cabinet is opened and closed.

65 13. A treating cabinet provided with a compartment for receiving the occupant, a mixing chamber provided with means for admitting air to same, a heating means in said mixing chamber, a fan chamber communicating with said compartment, an air chamber, a valve that is adapted to be arranged in one position so as to establish communication between said fan chamber 90 and said mixing chamber and in a different position so as to establish communication between said fan chamber and said air chamber, a passageway leading from said compartment to said mixing chamber, and a 95 valve in said passageway that is adapted to be arranged in one position so as to close said passageway and in a different position so as to establish communication between said passageway and said air chamber.

100 14. A treating cabinet provided with a compartment for receiving the occupant, a mixing chamber provided with means for admitting air to same, a heating means in said mixing chamber, a fan chamber communicating with said compartment, an air chamber, a valve that is adapted to be arranged in one position so as to establish communication between said fan chamber and said mixing chamber and in a different 105 position so as to establish communication between said fan chamber and said air chamber, a passageway leading from said compartment to said mixing chamber, a valve in said passageway that is adapted to be arranged in one position so as to close said passageway and in a different position so as to establish communication between said passageway and said air chamber, a 110 head compartment, a discharge chamber communicating with said head compartment, and means for positively cutting off communication between said passageway and the compartment in which the body of the occupant is arranged when said head 115 compartment and discharge chamber are in use.

15. A treating cabinet provided with compartments for receiving the head and body of the occupant, a movable partition be- 120

tween said compartments, means for ventilating the head compartment, a mixing chamber provided with means for heating a treating medium, a fan chamber provided with a slowly revolving fan and separated 5 from the body compartment by a slatted partition or similar means, a passageway communicating with said mixing chamber and provided with branches that lead to dif-

ferent sections of said body compartment, an air chamber, and means whereby a 10 heated treating medium can be circulated through said body compartment or a cooling medium can be circulated through said body compartment at the will of the attendant in charge of the cabinet.

ERIC H. GOLDEN.
